VERTICALLY SLIDABLE CLOSURE

Nicholas R. Guilbert, Jr., Chestnut Hill, Pa.

Application November 22, 1937, Serial No. 175,791

4 Claims. (Cl. 20—19)

This invention relates to improvements in vertically slidable closures and is of special advantage in dumb-waiter doors and the like in which a relatively heavy door must be raised and lowered by hand as it is directed primarily to improvements in supporting mechanism for such doors or other closures whereby the facility with which they may be raised and lowered is materially enhanced.

10 It is the practice to counterbalance the weight of doors of this class either by counterweights or by spring balances to enable the operator to open the door without actually lifting its entire weight and also to prevent it from falling shut again after it has been opened, and mechanism embodying my invention is particularly adapted for association with such doors counterbalanced by means of spring balances as it provides means whereby the counterbalancing springs may be readily and quickly adjusted to insure a proper suspension of the door and thereby prevent it from sticking through unequal tension of the springs on its opposite sides.

15 It is therefore a principal object of the invention to provide, in combination with a dumb-waiter door or other vertically slidable closure and counterbalancing mechanism therefor, means adapted to facilitate adjustment of such mechanism to insure equal counterbalancing of the opposite sides of the door, as well as to compensate for slight inequalities therein whereby the door is afforded equal support from its opposite sides and the ease with which it can be raised and lowered thereby enhanced.

20 Another object of the invention is to provide improved anchoring mechanism for the fixed ends of dumb-waiter door counterbalancing means whereby the tension of each of said means reacts against that of the other so that they are maintained in equilibrium with respect to the door to cause the latter to travel smoothly on its ways or tracks.

25 Other objects, purposes and advantages of the invention will hereinafter more fully appear or will be understood from the following description of a preferred embodiment thereof as illustrated in the accompanying drawing.

In the said drawing

30 Fig. 1 is a fragmentary front elevation of the assembled dumb-waiter door mechanism removed from the hatchway.

35 Fig. 2 is a vertical section thereof on the line 2—2 in Fig. 1.

40 Fig. 3 is a fragmentary view on an enlarged scale, partially in plan and partially in horizon-

tal section principally on line 3—3 in Fig. 1, showing the said mechanism applied to a typical dumb-waiter hatchway.

Fig. 4 is a fragmentary enlarged detail of a portion of Fig. 2 in which the door is shown in raised position.

In the several figures like characters are used to designate the same parts.

Referring now more particularly to the drawing, the door 1, preferably made of sheet metal, is rectangular in shape with its side edges turned at right angles to its general plane to form edge surfaces of substantial width, thereby giving the door the form of a shallow tray, the turned edges constituting the top, bottom and sides of the door. This door is arranged to slide vertically in the dumb-waiter hatch, the plane of the inside of the front wall of which is indicated by the line W in Fig. 2, and has secured to each of its sides adjacent the top and bottom a pair of track engaging shoes 2 adapted to receive one flange of an angle rail forming a track 3 which extends from the bottom of the hatch opening to a point appreciably above its top and serves to guide the door. The lower portions of tracks 3 at the sides of the hatch opening are secured to the walls W of the hatchway by bolts 4 which support them from angle rails 5 fixed in any suitable manner to the said walls while the upper parts of the tracks have angle brackets 6 fastened to them and to the wall to afford them additional lateral support. At the lower corners of the door are secured a pair of plates 8 which extend beyond the sides of the door for attachment of the spiral steel ribbons 9 of the spring balances 10 which counterbalance the weight of the door.

These balances are of a usual form well known in the art and each comprises a relatively long metal tube 11 with its upper end anchored in a manner hereinafter described, enclosing a coil spring secured at its upper end inside the top of the tube and at its lower end to a rotatable bushing in the latter. The spiral ribbon 9 is slidable in a corresponding spiral slot in this bushing so that when the door is lowered the spiral form of the ribbon causes the bushing to rotate in a suitable direction to load the spring and thus place it under tension and in condition to assist subsequent raising of the door, during which the bushing turns in the opposite direction under the influence of the loaded spring. Spring balances of this character are in general use and the specific form of balance employed constitutes no part of the invention.

so its details of construction and certain of the parts just described are not shown in the drawing but will be readily understood by those skilled in the art.

5 The upper ends of tracks 3 are rigidly interconnected by a cross bar 12 which serves to hold them in properly spaced relation and the spring balances 10 are connected with and suspended from this bar as now to be described.

10 An angular beam 15 extends substantially horizontally adjacent bar 12 and is pivoted to it on a bolt 16 in such a way as to support the beam from the bar to permit its limited oscillation in a vertical plane. The beam ends terminate just

15 short of the upper ends of spring balance tubes 11 and respectively support substantially similar plates 17 which are secured as by screws 18 or in any other suitable way to the top flange of the beam and project oppositely outwardly beyond its ends. Each of these plates is provided

20 with a circular hole 20 through which the upper end of the adjacent tube 11 extends and the latter is suspended from the plate on a pin 21 passing through a transverse hole in the tube

25 and overlying the top of the plate. As adjustment of the balances is effected by turning the tubes relatively to their enclosed bushings, to increase or decrease the spring tension it is essential to prevent them from turning after proper

30 adjustment has been made and further essential that the pins be kept in place in order to properly support the balances from the beam, and to this end suitable means are provided consisting, in the embodiment of the invention 35 shown, of an eye formed at one end of each pin and a screw 22 extending therethrough and into the subjacent plate 17; thus, when the screw is removed the tube can be turned to any desired extent and thereafter held against turning by 40 threading the screw into the plate through the eye which also secures the pin in place.

In addition to the supporting and guiding means just described the door is provided with a handle 25 which extends vertically adjacent its lower edge and has rubber or other resilient bumpers 26, 27 projecting from its opposite ends. The bumper 26 preferably extends slightly below the adjacent lower edge of the door for engagement with the sill 28 of the hatch opening when

50 the door is lowered, while the bumper 27 on the top of the handle is adapted for similar engagement with the header 30 of the hatch opening when the door is raised, these bumpers thus constituting resilient stops to bring the door to rest 55 at the limits of its travel and as they are fixed on the door handle with the latter in vertical position they also effectively prevent the hand of the operator being crushed against either the sill or the header by the handle while closing 60 or opening the door.

The mechanism just described affords a facility of adjustment of the balancing springs which materially simplifies the installation of the door in proper operating condition, while of course 65 readjustment after installation can as readily be made when and if necessary.

Thus as the relatively fixed ends of the spring balances are supported from a substantially horizontally extending beam pivoted at its center and 70 adapted for oscillation in a vertical plane, it is evident that it can easily be recognized by the horizontal position of this beam when an equalized adjustment of the balances has been effected, since if one balance is too tightly adjusted with 75 respect to the other the beam will be moved on

its pivot so as to tilt toward the too tightly adjusted balance. The beam thus indicates at all times whether either balance needs adjustment and, if it does, the nature of the adjustment required; that is, if the beam is tilted toward 5 the right in Fig. 1 it indicates the right hand spring balance should be relieved of some of its tension or the tension of the left hand balance increased to thereby equalize the tension the balances respectively exert upon the door. It is 10 usually desirable to have some lateral play between shoes 2 and tracks 3 to enable the door to slide freely, and consequently when the balances are properly adjusted, beam 15 can oscillate 15 slightly on its pivot in response to any resultant slight lateral movement of the door while it is being raised or lowered; the pivotal mounting of the beam thus always maintains the balances in exact and correct relation to the door to prevent it from sticking or jamming against the tracks. 20

Furthermore, if after proper initial adjustment the balances should in time exert unequal force on opposite sides of the door, due to unequal stretching of the springs or for any other reason, the inequality will result in tilting beam 15 toward the balance exerting the greater force, thus affording a readily observable visual indication of the need for readjustment which can then be promptly effected after removing one or both 25 screws 22.

While I have herein described a preferred embodiment of the invention as it may be incorporated in a dumb-waiter door assembly of a type well known in the art, it will be understood 30 that the invention is not limited or confined thereto or to employment solely in association with dumb-waiter doors as mechanism constructed in accordance therewith may advantageously be utilized in association with vertically slidable closures of various character, while changes and 35 modifications in the form, construction and arrangement of the several parts will readily occur to those skilled in the art and may be made if desired, without departing from the spirit and 40 scope of the invention as defined in the appended 45 claims.

Having thus described my invention, I claim and desire to protect by Letters Patent of the 50 United States:

1. In combination with a vertically slidable closure, counterbalancing means supporting the closure from its opposite sides, a pivoted substantially horizontal beam disposed above the closure, and means for supporting the counterbalancing means from the opposite ends of said beam. 55

2. In combination with a slidable closure, guide shoes carried by the closure, vertical tracks extending adjacent its opposite sides respectively 60 adapted to receive said shoes, a cross bar extending between the tracks above the upper limit of travel of the closure, a rigid beam pivoted adjacent the center of the cross bar for oscillatory movement in a vertical plane, and counterbalancing means for the closure extending between the respective ends of the beam and the corresponding lateral extremities of the closure. 65

3. In combination with a vertically slidable closure, a pivoted substantially horizontal beam 70 disposed above the closure, a pair of spring balances each comprising a tubular member and a relatively movable closure supporting element connected to the closure, and means for suspending the tubular members adjacent opposite ends 75

of the beam and restraining them from axial rotation.

4. In combination with a vertically slideable closure, a beam disposed above the closure and pivoted at its midpoint for vertical oscillation, a spring balance adjacent each end of the beam comprising a part projecting through and rotatable with respect to the beam and a subjacent

part attached to the closure, a pin extending transversely through said projecting part above the beam having an eye at one of its ends, and a screw passing through said eye and into the beam preventing longitudinal displacement of the pin from said part and restraining the latter from axial rotation. 5
